JOHN F. O'CONNOR, OF CHICAGO, ILLINOIS, ASSIGNOR TO WILLIAM H. MINER, OF CHAZY, NEW YORK.

FRICITION SHOCK-ABSORBING UNIT.

1,290,326.

Specification of Letters Patent.

Patented Jan. 7, 1919.

Application filed March 12, 1916. Serial No. 221,933.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Units, of which the following is a full, clear, concise, and exact description, reference being had to the accompanying drawings, forming a part of this specification.

This invention relates to improvements in friction shock absorbing units.

Heretofore, attempts have been made to utilize a plurality of concentrically arranged friction spring plates between two followers to absorb shocks, the concentric spring plates being squeezed or compressed and their diameters reduced as the followers come together. With this arrangement, a large frictional wearing area is, of course, provided between the spring plates with consequent higher capacity and longer life. However, in actual practice, it has been found that devices of this type heretofore made have proved unsatisfactory due to the fact that upon approach of the followers, the pressure from the followers to the springs is applied at four points, and these points cause the concentric spring plates to be pinched or distorted and the necessary gradual reduction of the diameters or circumferences of the spring plates is not obtained. In other words, to insure proper compression of the spring plates, it is necessary to provide for a gradual and substantially uniform decrease of the circumference of the spring plates which cannot be obtained where the spring plates are in contact with the followers at four points which do not shift during the operation of the mechanism.

The object of the present invention is to provide a simple arrangement whereby the springs can be squeezed or decreased in circumference uniformly and without danger of pinching the spring plates.

In the drawings forming a part of this specification, Figure 1 is a part elevational view, part longitudinal, vertical section, of a railway draft rigging showing one of my shock absorbing units employed therewith. And Fig. 2 is a part horizontal, sectional view, part top plan of a portion of a tandem

railway draft rigging showing two of my units employed therewith.

The shock absorbing unit may be employed with a gear of the single type, as shown in Fig. 1, or with a gear of the tandem type, as shown in Fig. 2, the structure of the unit being the same in either case, and I do not deem it necessary to describe the parts of the draft rigging, since these are well known to those skilled in the art.

The shock absorbing mechanism proper consists of a pair of followers A—A, four blocks B—B and a plurality of concentrically arranged spring plates C.

Each follower A is provided with an end wall 10, parallel side walls 11—11, and two inner oppositely inclined upper and lower walls 12—12.

The series of springs C are preferably made concentric, each coil being somewhat less than a complete circle so as to permit of the necessary contraction of the coils as the latter are compressed. The coils are arranged with their axes at right angles to the line of relative movement between the followers A—A, as clearly appears from Fig. 1.

Each of the blocks B is provided on its inner face with a curved surface 13 adapted to conform to the outer spring plate C. On its outer face, each block B is provided with an inclined surface 14 coöperable with the adjacent inclined wall 12 of the follower.

As will be understood, the followers are normally separated, as clearly shown in Figs. 1 and 2, and when in their normal separated position and with the spring plates C expanded to their maximum, the blocks B will assume the position shown in Fig. 1, that is, said blocks B will assume the highest and lowest positions possible with respect to the followers A, their position being determined by engagement with the flanges 15—15 on the tops and bottoms of the followers A. The inclined surfaces or walls 12 and 14 are so designed that, when all the parts are in normal position, diameters drawn through the axes of the concentric spring plates perpendicular to the said inclined surfaces 12 and 14 will be perpendicular to each other, as indicated, for instance, by the dotted lines 16 and 17 in Fig. 1.

As the followers are moved relatively toward each other, the spring plates will be compressed and their circumference

reduced and in this process, it is evident that the blocks B will slide relatively to the followers A on the surfaces 12 of the latter, but in all positions of the parts, the blocks B will remain diametrically opposite each other with respect to the spring plates C. In this manner, I avoid the pinching effect which has heretofore accompanied the operation of friction shock absorbing devices of a somewhat similar character and I am, therefore, enabled to obtain a true sliding frictional effect between all the coils of the concentric spring plates and also between the outermost spring plate and all 15 of the blocks B. There is, of course, the additional friction generated between the blocks B and the followers A due to the blocks B sliding on the followers. The followers may be so designed that they will 20 come into engagement with each other to thereby limit the compression of the spring plates and if desired, the followers A may have side enlargements 18-18 to coöperate with limiting stops 19 of a railway stop 25 casting, as shown in Fig. 2.

I have herein shown and described one manner of carrying out my invention but the same is merely illustrative and I contemplate all changes and modifications that 30 come within the scope of the claims appended hereto.

I claim:

1. In a friction shock absorbing unit, the combination with a pair of followers relatively movable toward each other, of a plurality of substantially circular springs with their axes arranged perpendicular to the line of relative movement between said followers, blocks mounted on said followers 35 and curved on their inner faces to conform to said springs, said blocks being shiftable on said followers when the latter are moved relatively toward each other to thereby compress said springs and gradually decrease their circumference.

2. In a friction shock absorbing unit, the

combination with a pair of followers relatively movable toward each other, of a series of concentrically arranged spring plates having their axes perpendicular to 50 the line of relative movement between said followers, blocks mounted on said followers and curved on their inner faces to conform to said spring plates, said blocks being shiftable on said followers when the latter 55 are moved relatively toward each other to thereby compress said springs and uniformly decrease their circumference.

3. In a friction shock absorbing unit, the combination with a pair of followers relatively movable toward each other, each follower having a pair of oppositely inclined surfaces on its inner face, of a plurality of substantially circular springs interposed between said followers, four blocks, one 60 mounted on each of said inclined surfaces of the followers, said blocks being curved on their inner faces to conform to said springs, said blocks being slidable over said inclined surfaces when the followers are moved relatively toward each other.

4. In a friction shock absorbing unit, the combination with a pair of followers relatively movable toward each other, each of said followers having a pair of oppositely 65 inclined surfaces on its inner face, of a plurality of concentrically arranged frictionally engaging spring plates disposed between said followers, and four blocks, one mounted on each of said inclined surfaces of 70 the followers, said blocks being curved on their inner faces to conform to the outer most spring plate, said blocks being movable over said inclined faces of the followers as the followers are moved relatively 75 toward each other to thereby uniformly decrease the circumference of said spring plates and compress the latter.

In witness that I claim the foregoing I have hereunto subscribed my name this 26th 90 day of Feb., 1918.

JOHN F. O'CONNOR.
